CLAMP SUPPORT

Forester E. Woodruff, McKinney, Tex., assignor
of one-half to Howard S. Ware, McKinney,
Tex.

Application April 25, 1935, Serial No. 18,272

2 Claims. (Cl. 248—74)

This invention relates to an improved clamp support and is particularly adapted for clamping and supporting the neutral wire and ground wire used in electric line installations.

One object of the invention is to provide a support which, after installation on a pole, will effectually retain the neutral wire of an electric line installation in position and also provide an effective means by which a ground wire may be rigidly connected to said neutral wire.

Another object of the invention is to provide a support which is formed of companion sections fitted together and secured to a pole or other mounting means by a single fastening device, so that the use of solder, wire, or other connecting devices, is dispensed with.

Another object of the invention is to provide a support wherein the companion sections are effectually connected together in operative position at several points throughout their length but which, when the single fastening device is loosened, may be readily separated.

A further object of the invention is to provide a device of this character wherein the companion sections may be rocked away from each other while in position but before tightening, so that the neutral wire and ground wire may be placed therein without removing the entire device from the mounting post.

And a still further object of the invention is to provide a support which will be simple in construction and which may be manufactured with facility in large quantities.

Other and incidental objects of the invention will render themselves apparent during the course of the following description.

Referring now to the accompanying drawing:

Figure 1 is a side elevation showing my improved support as it would appear in operative position with a neutral wire and a ground wire secured therein.

Figure 2 is an enlarged longitudinal sectional view, partly shown in elevation, and illustrating how the neutral wire and ground wire would appear in operative position in the support.

Figure 3 is an enlarged longitudinal sectional view on the line 3—3 of Figure 2, looking in the direction indicated by the arrows.

Figure 4 is a vertical sectional view on the line 4—4 of Figure 2.

Figure 5 is a vertical sectional view on the line 5—5 of Figure 2 and showing, in dotted lines, the position of one of the companion sections when said sections are spread to receive the neutral wire.

Referring now more particularly to the accompanying drawing, wherein like numerals of reference designate like parts throughout the several views, the numeral 1 indicates a mounting post to which is connected, at its upper end portion, an insulator 2 which supports a high tension wire 3. A neutral wire 4 is associated with the post beneath the high tension wire 3, and a ground wire 5 is also associated with the post and is embedded in the earth at its lower extremity, 10 in the usual manner.

Associated with the post and connecting the neutral wire 4 and the ground wire 5 thereto, is my improved clamp support which comprises companion sections 6 and 7 which are preferably 15 cast from metal and are relatively large in diameter at their central portions and taper in thickness toward their opposite ends. The companion sections are identical in construction so that a description of one will suffice for both.

A typical section includes a semi-circular wall 8 and a flat face 9 extending throughout the length of said section. The section is tapered in diameter from the middle toward its opposite ends. Formed in the section medially of its 25 length is an opening 10 which is gradually enlarged elliptically and vertically near its outer end, as indicated at 11. The section 7 is formed with a like opening. The purpose of the enlarged opening will be described hereinafter. Formed 30 in the section 6 and extending throughout its length is a straight V-shaped trough or recess 12 which is adapted to receive the neutral wire 4. The recess 12 cooperates with a like oppositely disposed recess in the companion section 7 to 35 define an opening. Formed on the section 6 beneath the recess 12, and at one side of the opening 10, is a protuberance or locking pin 13, while formed in said section at the other side of said opening is a socket 14. It should be understood 40 that the pin 13 is adapted to engage in an oppositely disposed socket in the section 7, as shown in Figure 3, while the socket 14 is adapted to receive a corresponding pin 15 which is formed on the section 7. As seen in Figures 3 and 5 of 45 the drawing, the end portions of the pins 13 and 15 are rounded so that they will be readily permitted to tilt, or shift in and out of their respective sockets. The cooperating pins and sockets prevent relative longitudinal movement of the 50 two sections when the device is in use and also prevents possible relative rotative movement of the two sections. Formed on the section 6 at the enlarged portion thereof, are stops 16.

Extending through both of the sections and 55

through the post 1, or like supporting element, is a bolt 17 which is provided with a preferably squared head 18 adapted to fit between the stops 16. Said stops will, of course, limit the head 5 against rotative movement when the same is abutted against the section 7. It should be understood that the bolt 17 serves the dual purpose of connecting the sections to each other and also connecting the entire device to the post. A suitable retaining nut 19 is screwed on the free end 10 of the bolt 17 for retaining the entire assembly in position.

As can be best seen in Figure 2 of the drawing, the neutral wire extends throughout the length 15 of the recess 12 and has wound thereabout the ground wire 5. The clamp support will, as will be understood, rigidly connect the ground wire 5 and neutral wire 4 to each other and will retain said wires in operative position on the post 1. As seen 20 in dotted lines in Figure 5 of the drawing, when it is desired to remove the neutral wire 4 and the ground wire 5 from the clamp support, it is only necessary to loosen the bolt 17 to such an extent 25 that the sections may be spread apart for permitting the removal of said wires from between the sections. The use of the enlarged openings 11 permits the sections to shift away from each other upon the bolt so that ready separation of the sections 30 may take place. As the pins 13 and 15 are rounded at their free ends, said pins will permit the sections to swing apart and, as shown in dotted lines in Figure 5, when said sections are separated, the top portions of the pins will engage the top of the recesses 14 at the mouths 35 thereof so that complete separation, with consequent relative rotation of the sections, will not take place. The stops 16, of course, prevent rotation of the head 18 of the bolt 17 when the device has been secured in position so that the nut 19 40 may be tightened to the desired degree. It should be understood that the walls of the V-shaped recesses cooperate for clamping the ground wire to the neutral wire as well as effectually supporting both wires between the sections. The recesses 12 45 are flared at their ends to prevent chafing of the wire passing through said recesses.

It is believed that from the foregoing it will

be seen that I have provided a simple and highly efficient clamp support which may be placed in use with the utmost facility and which will need little or no attention after initial installation.

Having thus described the invention, what I 5 claim is:

1. A clamp support including companion sections, each formed with a longitudinal V-shaped recess defining an opening, alined openings formed in the sections medially and transversely 10 thereof and being elliptically enlarged vertically toward their outer ends, and a bolt extending through said alined openings and adapted for clamping the sections to each other and to a support whereby a wire in the first mentioned opening 15 will be secured in position against the walls of the V-shaped recesses, said enlarged openings permitting tilting of the sections away from each other when the bolt is loosened for permitting removal of the wire from the first mentioned open- 20 ing.

2. A clamp support including companion sections having V-shaped longitudinal recesses formed therein defining an opening between the sections to receive a neutral wire and a ground 25 wire having its end portion wound thereabout, a pin carried on one of the sections at one end and a recess formed in said section at the opposite end, a pin and recess similarly formed on the other of said sections, said pins and recesses being adapted for cooperating for retaining the sections in proper relative position and said pins being formed with rounded end portions, said sections being formed with openings medially there- 30 of and said openings being enlarged toward their outer ends, and a bolt extending through said second mentioned openings and adapted for connecting the sections to each other and to a supporting element, the walls of said V-shaped recesses clamping the ground wire to the neutral 35 wire and both of said wires within the recess, and said rounded end portions of said pins cooperating with the enlarged openings for permitting tilting of the sections away from each other and removal of the wires when the bolt is loosened. 40 45

FORESTER E. WOODRUFF.
